DRAFT AND BUFFER GEARING

Glenn E. Edmunds, Columbus, Ohio, assignor to
 The Bonney-Floyd Company, Columbus, Ohio,
 a corporation of Ohio

Application March 29, 1934, Serial No. 718,047

2 Claims. (Cl. 213—9)

The present invention relates to draft and buffer gearing of general application, the gearing being of the type wherein shock absorbing means serve the dual function of opposing draft and impact forces. According to the invention, however, additional shock absorbing means are provided for the impact forces, these latter being inoperative so far as draft forces are concerned. Still more particularly, the invention relates to an arrangement of the shock absorbing means whereby compactness is enhanced and other advantages are secured as will be understood from the following description of a specific embodiment of the invention as shown in the accompanying drawings, in which:

Figure 1 is a plan view partly broken away of the draft and buffer gearing assembly.

Figure 2 is a face view, with parts broken away of the assembly of Figure 1.

Figure 3 is a section substantially on line 3—3 of Figure 1.

Figure 4 is a section substantially on line 4—4 of Figure 1, and

Figure 5 is a face view of a draft member.

For the sake of convenience, supporting means for the draft and buffer elements is shown as being in the form of a bracket 10 attachable to a car end, the gearing being entirely self-contained in the bracket. Bracket 10 comprises parallel top and bottom webs 11 and 12, of which the top web is provided with a forward central recess 13, while the bottom web beneath recess 13 has a downward offset 14. The top and bottom webs are connected at their ends by means of side webs 15 and 16, which have vertical faces, prolonged into arms 17 and 18 which may be secured to the ends of longitudinal sill members, not shown, forming structural elements of a car. Webs 11, 12, 15 and 16, which are preferably integral, are integrally joined by a rear wall 19 which is substantially triangular in plan with its apex projecting in the longitudinal direction of arms 17 and 18 and midway between the two.

Formed on the forward face of wall 19 adjacent the outer ends thereof and medially in the vertical direction are a pair of spring seats of which one is shown at 20, Figures 1 and 3, these seats providing seating surfaces normal to the planes of arms 17 and 18 and having centering bosses as at 21.

A draft member 22 is in the form of a bar comprising a front wall 23 and top and bottom webs or flanges 24 and 25. The bar has rectilinear top and bottom front edges, the rear edges of webs or flanges 24 and 25 being triangular so as to con-

tact substantially throughout with the front or inner face of wall 19. Wall 23 is centrally rearwardly offset as at 26 in substantially concentric relation to aligned apertures 27 and 28 formed in webs 24 and 25, the offset wall portion 26 defining a pocket in which is received the shank 29 of a draft hook 30. Webs 11 and 12 are provided with slots 31 and 32 extending in the longitudinal direction of arms 17 and 18 and registering in part with apertures 27 and 28. A bolt 33 is passed through the slots and apertures and carries washers 34 and 35 externally of walls 11 and 12 and of such dimension as to close slots 31 and 32. In advance of the slots, webs 11 and 12 have formed thereon rectilinear flanges 36 and 37 in a common plane normal to the outer surfaces of arms 17 and 18, these flanges being utilizable in securing the bracket to the car end wall, it being here assumed that the rear portion of the bracket is to be positioned in a transverse slot formed in the end wall. The relation of parts is such that upon the application of the draft to hook 30 bolt 33 can move forwardly to the ends of slots 31 and 32. Hook 30 has a heel portion supported on the offset web portion 14, so that the weight of the draft linkage has no distortional effect on bar 22.

Bar 22, immediately in front of the spring seats as at 20, is provided with circular apertures 38 and the forward face of wall 23 is provided with arcuate ribs as at 39 at the sides of the apertures in spaced relation to the edges thereof.

In front of the ends of bar 22 are buffer means 40 and 41 slidably supported between webs 11 and 12. The buffer means are here shown as comprising two separate heads, but it will be understood that the use of buffer means in the form of a single bumper is contemplated under the invention, when preferred. Heads 40 and 41 are identical and a description of the latter, which is more completely shown, will suffice for both.

Head 41 comprises top and bottom walls 42 and 43 spaced apart for free sliding movements between bracket webs 11 and 12. Walls 42 and 43 are joined by side walls 44 and 45 to form a box-like structure closed forwardly by an integral buffering face 46 which toward wall 44 is in a plane substantially perpendicular to the plane of walls 44 and 45 but is rounded toward both and with a rather gradual curve toward wall 45.

Walls 42 and 43 of the head 41 are provided with registering slots 47, 48 and 49, 50. Slots 47 and 48 may have parallel side walls as shown in Figure 2, while slots 49 and 50 are preferably enlarged at the forward ends toward wall 44 as particularly shown in Figure 1. Webs 11 and 12

have registered apertures 51, 52 and 53, 54 registering likewise, in part, with the slots in the buffer head and receiving pins 55 and 56.

Formed on the inner side of the face 46 and 5 immediately opposite aperture 38 is a spring seat 57 parallel, in the position of parts shown, to the surface of seat 20. Seat 57 is provided centrally with a centering boss 58 and outwardly of the latter with arcuate ribs 59. A spiral compression spring 60 bears with its ends against seats 20 and 57 to be centered thereon by bosses 21 and 58, the spring passing freely through an aperture 38. A further spiral compression spring 61 is arranged in concentric surrounding relation to spring 60 and with its ends bears against wall 23 of bar 22 and seat 57, being centered at its ends by ribs 39 and 59. The springs 61 normally hold the bar in the illustrated position, Figure 1.

20 As above stated, head 40 is exactly the same as head 41 and is mounted and associated with the bracket and draw bar and spring-influenced in exactly the same manner as head 41, being in connection with the bracket by means of pins 25 62 and 63. It will be understood, however, that head 40 is the other side up, as compared to head 41, to afford a symmetrical arrangement.

The assembly of the described parts is very simple. Draw bar 22 is first inserted to the position shown in Figure 1, whereupon the draft hook 30 is positioned therein and bolt 33 is dropped into place. Hereupon, the springs are placed in position and the heads 40 and 41 inserted to position between webs 11 and 12, whereupon the retaining pins for the heads are dropped into place.

Upon the application of draft to hook 30, the draw bar may move outwardly of the bracket against the force of the springs as at 61, the springs as at 60 being unaffected by reason of 40 their free passage through the apertures in the wall. Draft is thus transmitted through the springs as at 61 to the buffer heads and through the connecting pins for the latter to the bracket. Outward movement of the draw bar is limited 45 through abutment of bolt 33 with the forward ends of slots 31 and 32. Under impact each head moves toward the draw bar against the force of both of the associated springs. The springs associated with each head are concentrically nested 50 on axes symmetrical with respect to the heads, so that direct impacts on the flat buffer faces are transmitted without any distortional effect. In rounding curves the heads may pivot on the inner pins 55 and 63, this being permitted by the 55 shape of the outer slots as at 50, Figure 1.

It will be understood that various modifications may be made in the form and arrangement of parts and consequently I do not limit myself in these respects except in the following claims.

60 I claim:

1. Car draft and buffer gearing comprising supporting means, buffer means and a drawbar carried by said supporting means and movable relative thereto toward and away from each

other, said buffer means being disposed outwardly of said drawbar and being constituted by separably movable heads spaced horizontally, said drawbar having end portions lying behind said heads, respectively, and provided with apertures, 5 an upright wall inwardly of said drawbar fixed with respect to said supporting means and constituting an abutment for limiting inward movement of said drawbar relative to said supporting means, means for limiting outward movement of 10 said buffer heads relative to said supporting means, opposed spring seats on said upright wall and the respective buffer heads aligned with said drawbar apertures, spiral compression springs of a size to pass freely through said apertures 15 having their ends engaged with the opposed seats, and further spiral compression springs freely surrounding the first and having their ends seated, respectively, against said drawbar and said buffer means, said further springs serving to 20 hold said drawbar normally against said wall and serving to transmit draft forces exclusive of the first springs, the springs of each set of nested springs serving to hold their associated buffer head normally in outer limit position and 25 both springs of each set acting immediately to absorb buffing shocks transmitted by their associated buffer head.

2. Car draft and buffer gearing comprising supporting means, buffer means and a drawbar 30 carried by said supporting means and movable relative thereto toward and away from each other, said buffer means being disposed outwardly of said drawbar and being constituted by separably movable heads spaced horizontally, 35 said drawbar having end portions lying behind said heads, respectively, and provided with apertures, an upright wall inwardly of said drawbar fixed with respect to said supporting means and constituting an abutment for limiting inward 40 movement of said drawbar relative to said supporting means, means for limiting outward movement of said buffer heads relative to said supporting means, opposed spring seats on said upright wall and the respective buffer heads 45 aligned with said drawbar apertures, spiral compression springs of a size to pass freely through said apertures having their ends engaged with the opposed seats, and further spiral compression springs freely surrounding the first and having 50 their ends seated, respectively, against said drawbar and said buffer means, said further springs serving to hold said drawbar normally against said wall and serving to transmit draft forces exclusive of the first springs, the springs 55 of each set of nested springs serving to hold their associated buffer head normally in outer limit position and both springs of each set acting immediately to absorb buffing shocks transmitted by their associated buffer head, the springs as- 60 sociated with each head being substantially coaxially disposed and exerting a symmetrical ac- tion on such head.

GLENN E. EDMUND.
